CLAIM

We claim the ornamental design for a football helmet, as shown and described.

DESCRIPTION

FIG. 1 is a perspective view of a football helmet showing our new design;

FIG. 2 is a front view of the football helmet of FIG. 1; FIG. 3 is a left side view of the football helmet of FIG. 1, the right side being a mirror image thereof; and, FIG. 4 is a top view of the football helmet of FIG. 1. Features shown in broken or dashed lines in the drawings are not part of the claim. Any shading presented in the accompanying drawings is provided merely to highlight the contour of the invention and is not intended to be illustrative of texture or gloss.
